UNITED STATES PATENT OFFICE.

JAMES M. MAJORS, OF OTTUMWA, IOWA.

THREAD-CUTTER AND SPOOL-HOLDER.

1,295,549.

Specification of Letters Patent. Patented Feb. 25, 1919.

Application filed January 24, 1918. Serial No. 213,454.

To all whom it may concern:

Be it known that I, JAMES M. MAJORS, a citizen of the United States, and resident of Ottumwa, in the county of Wapello and

5 State of Iowa, have invented a new and useful Thread-Cutter and Spool-Holder, of which the following is a specification.

The object of my invention is to provide a thread cutter and spool holder of simple, 10 durable and inexpensive construction.

A further object of my invention is to provide a stand having spool holding devices secured thereto, a combination thread guiding and gripping member and a cutting 15 blade.

A further object of my invention is to provide such a base having a thread holder and blade thereon with a device adapted to hold and guide the thread therethrough so 20 that the thread may be freely pulled from the spool until the latter is drawn in the direction toward the cutting blade where it will be retarded to furnish sufficient tension to cut the thread as it is pulled across the 25 cutting blade.

A further object of my invention is to provide a thread guide and tension provided with means for accommodating two or more threads, so that several spools may be 30 mounted upon the base without interfering with each other.

A further object of my invention is to provide an upright stand having formed thereon a pair of intersecting thread guides 35 arranged with their bottoms in horizontal alinement at the intersection of the guides, so that a single thread may be arranged to be simultaneously pulled through the intersecting guides at the same time whereby if 40 the thread, which is being pulled on is pulled in such direction that it would force the portion of it in the guide down against the other portion of the thread, which is in the other thread guide, then it will prevent the 45 thread from being pulled through the guides thereby furnishing tension sufficient to permit the free end of the thread to be drawn across the cutting blade and severed from the portion still connected to the spool.

50 A further object of my invention is to provide an upright strip of material having a pair of vertical intersecting cuts made in its upper end, which have their bottoms in substantially the same horizontal plane at 55 the point where the cuts intersect, so that a

thread may first be drawn through the bottom of one cut and then wrapped around a portion of the post to position where it may be extended through the other cut.

It will be seen that when the thread has 60 been placed in this position, a pull on the free end of the thread will cause the portion thereof at the intersection of the cuts to frictionally engage the portion of the thread which is extended through the other cut 65 thereby furnishing a tension which prevents more thread being pulled through the post while the pull is continued in the same direction.

A further object of my invention is to 70 provide a post having the intersecting cuts hereinbefore mentioned and which also has the cut through which the free end of the thread is pulled made somewhat deeper than is the other cut whereby the thread in the 75 second cut may be somewhat looped by a downward pull on the thread in the first cut to furnish a more efficient tension.

With these and other objects in view, my invention consists in the construction, ar- 80 rangement and combination of the various parts of my device whereby the objects contemplated are attained, as hereinafter more fully set forth, pointed out in my claims, and illustrated in the accompanying drawings, 85 in which:

Figure 1 shows a perspective view of my improved spool holder and thread cutter.

Fig. 2 shows a front elevation of a portion of the combined guide and tension device 90 having parts broken away to better illustrate the construction.

Fig. 3 shows a vertical, sectional view taken on the line 3—3 of Fig. 2.

Fig. 4 shows an enlarged detail view of a 95 portion of the parts shown in Fig. 3 but with the thread removed, and

Fig. 5 shows an enlarged detail view partly in section of the tension and thread guiding device shown in Fig. 2 but having 100 the thread removed.

Referring to the accompanying drawings, I have used the reference numeral 10 to indicate generally a base having at one end a pair of upwardly extending blocks 11 be- 105 tween which may be secured a cutting blade 12. At the other end of the base 10 a pair of pins 13 are spaced from each other and extend vertically to support the spools 14 having thereon the thread 15. Between the 110

spools 14 and the blade 12 a stand 16 is secured to the base 10, which supports the thread guiding and tension device.

The latter consists of a horizontal bar 17, which is supported intermediate of its ends upon the base 16 and has at its ends upwardly extending posts 18. At the center of the bar 17 a pair of spaced, parallel, vertical fingers 19 are formed. An opening 20 may 10 be rounded out at the base of the fingers 19 to furnish a guide through which the thread 15 may extend from the spools 14. At the outer ends of the forward side of the bar 17, plates 21 are secured thereto. The inner 15 sides of the plates 21 extend inwardly from the inner face of the post 18. A cut or groove 22 is made or formed between the post 18 and the plate 21 which has its bottom about half way between the top and 20 bottom of the bar 17. A second cut or groove 23 is formed in substantially vertical alignment with the inner face of the post 18 and intersects the groove 22. The groove 23 may be formed, so that its bottom 24 is substantially aligned with the bottom of the groove 22 except at the forward end 25 where it may be inclined downwardly somewhat.

It has also been found desirable to make 30 a second groove in the bottom of the groove 23 of less width than the groove itself at 26. This latter groove is inclined somewhat downwardly from a point about the center of the bottom 24 of the groove 23. A pair 35 of resilient fingers 27 are secured to any convenient place as the stand 16 and extend upwardly and outwardly therefrom across the forward portion of the slot 23 and for a definite distance beyond the outer edges 40 of the plates 21 for a purpose hereinafter specified.

In the practical operation of my improved thread cutter and spool support the spools are placed on the pins 13 and the thread 45 thereon is carried up through the guide opening 20, then through the slot 22 around the post 18 through the slot 23 and thence downwardly toward the plate 12. In this connection it may be mentioned that after 50 the thread has been drawn through the opening 20 and is then carried laterally, it will readily and easily slide up the resilient finger 27 to proper position to be dropped downwardly into the slot 22, after which it 55 is wound around the post 18, dropped into the slot in the plate 21, and extended downwardly and toward the cutting blade 12 beneath the resilient finger 27.

The fingers 27 help prevent the accidental 60 removal of the thread from the slot in the plate 21.

Referring to Fig. 3 it will be seen that after the thread has been extended around the post 18 through the slots 22 and 23, a 65 horizontal or slight upward pull on the

thread 15 will permit it to pull freely and readily around the post 18. If, however, the pull on the thread be in a somewhat downward direction or toward the plate 12 the thread 15 will assume the position shown 70 in Fig. 4 and the portion extending through the slot 23 will be tightly pulled across the portion extending through the slot 22 thereby causing a frictional tension of greater or less strength depending upon the angle relative to the horizontal at which the thread is 75 being pulled from the slot 23.

Where a second smaller channel as is shown at 26 is provided in the bottom of the slot 23 experiments have shown that a 80 change of less than half an inch in the vertical direction of the pull of the thread 15 from the slot 23 will make the difference between breaking off the thread at the intersection of the slot 22 and 23 or of the thread 85 running with practically no tension thereon.

It will thus be seen that the plate 12 may be so placed that the thread 15 may be pulled from the slot 23 in practically any direction from the said slot without any appreciable 90 tension on the thread except when the thread is brought within less than half an inch of the upper edge of the cutting blade. The plate 12 is, of course, spaced a sufficient distance from the groove 23, so that the thread 95 left hanging from said groove is long enough to be readily grasped by the fingers.

The rear faces of the posts 18 are inclined downwardly and forwardly as shown in Fig. 3, so that if any tendency exists for the 100 thread to rise along the rear face of the post 18, any pull on the thread, which causes the thread to slide along said face, will also cause the thread to move downwardly thereon. It will thus be seen that whenever 105 thread is being pulled through the slot 23 the thread at the rear end of the slot will be at all times guided down to contact with the bottom of the wall of the inclination of the rear surface of the post 18. This feature 110 insures that when the direction of the pull on the thread is changed sufficiently to bring it near the plate 12 the thread will then contact with the cross thread in the wall 22 to properly lock the thread from movement. 115

I claim as my invention:

1. In a device of the class described, a base, a spool supporting member thereon, a thread supporting device on said base having a projecting member provided with intersecting guide grooves for guiding and holding a thread.

2. In a device of the class described, a base, a spool supporting member thereon, a thread supporting device on said base having a projecting member provided with intersecting guide grooves for guiding and holding a thread adjacent to said projecting member, said projecting member being tapering toward its portion adjacent to said guide 130

grooves to cause a thread drawn around it to slide toward said grooves.

3. In a device of the class described, a base, means for supporting a spool thereon, 5 means for supporting a cutting blade on said base in position spaced from said first described means; a post mounted on said base between said first two described means, said post having a pair of intersecting cuts 10 formed adjacent to its upper end and above

the upper edge of the cutting blade, said cuts having their bottoms substantially in horizontal alignment and resilient means suitably mounted and extending across the upper portion of one of said cuts whereby 15 the thread may be guided into the cut and resiliently held from being pulled out thereof.

Des Moines, Iowa, October 8, 1917.

JAMES M. MAJORS.
